DESIGN FOR A TIRE

William Edward Hardeman and Bernard William Deacon Lacey, Birmingham, England, assignors to Dunlop Tire and Rubber Corporation, Buffalo, N. Y., a corporation of New York

Application September 14, 1937, Serial No. 71,610
In Great Britain May 25, 1937

Term of patent 14 years

To all whom it may concern:—

Be it known that we, William Edward Hardeman and Bernard William Deacon Lacey, subjects of the King of Great Britain and residents of Acocks Green, in the city of Birmingham, county of Warwick, England, and Ward End, in the city of Birmingham, county of Warwick, England, respectively, have invented a new, original, and ornamental Design for a Tire, of which the following is a specification, reference being had to

the accompanying drawing, forming a part thereof.

Fig. 1 is a perspective view; Fig. 2 is a side elevation, and Fig. 3 is a top plan view of a section of a tire showing our new design.

We claim:

The ornamental design for a tire as shown.

WILLIAM EDWARD HARDEMAN.
BERNARD WILLIAM DEACON LACEY.
